United States Patent

Des. 239,742
Patented Apr. 27, 1976

239,742

SAFETY RAZOR

Arnold E. Rees, Blyth, England, assignor to
Wilkinson Sword Limited

Filed May 20, 1974, Ser. No. 471,206

Claims priority, application Great Britain Nov. 23, 1973

Term of patent 14 years

Int. Cl. D28—03

U.S. Cl. D95—3 A

FIG. 1.

FIG. 2.

FIG. 3.

FIG. 4.

FIG. 1 is a front elevational view of a safety razor showing my new design, the rear being substantially the same less the horizontal edge line immediately above the bottom edge;

FIG. 2 is a right side elevational view thereof, the left side being substantially a mirror image;

FIG. 3 is a top plan view thereof; and

FIG. 4 is a bottom plan view thereof.

I claim:

The ornamental design for a safety razor, as shown and described.
